UNITED STATES PATENT OFFICE

2,617,421

ELECTRODE

Charles Love Strong, London, England

Application September 12, 1951, Serial No. 246,220
In Great Britain November 1, 1949

1 Claim. (Cl. 128—416)

1

This invention relates to apparatus for carrying out electro-therapeutic treatments, and has for its chief object to provide a device which will facilitate the treatment of injuries, rheumatism and other ailments by rhythmic muscular contractions in horses, the treatment being carried out by faradic currents. In electro-therapeutic treatments, such as those referred to above, it is necessary, of course, to complete the circuit for the faradic current. It is usual to use an applicator which is carried in the operator's hand and moved about from place to place as required in order to carry out the desired treatment. In treating human beings, one electrode is strapped to, or held in place by the weight of, the body so that the circuit is completed through the body. The present invention is concerned with the fixed electrode, as distinct from the applicator, of such a system, and has for its chief object to provide a simple and very effective construction of the same for use in the treatment of horses.

The device according to the present invention is similar to a normal rugging roller for horses, but is characterised by the presence on the inside of the same of a mail or chain mail electrode adapted to extend down on either side of the horse's spine, a plug or socket being carried on the outside, whereby a readily detachable electric connection may be made to the mail or chain mail, and a sheet of waterproof material being interposed between the mail or chain mail and the material of the roller.

Conveniently, the mail or chain mail electrodes on the two sides of the horse's spine are separate from one another and are individually connected to the contacts of a plug or socket on the outside of the device.

In order that this invention may be the more clearly understood and readily carried into effect, reference may be made to the accompanying drawings, which illustrate by way of example one convenient embodiment of the present invention, and in which:

Figure 1 is a transverse section through the complete device.

Figure 2 is an underplan of the upper part of the device showing the chain mail electrodes, and

Figure 3 is a side elevation of the same.

Referring now to the accompanying drawings, the device for carrying out electro-therapeutic treatments on horses therein illustrated is similar to the usual rugging roller for use on horses which normally comprises an upper canvas part 10, which may be, say, eight inches wide, padded on the inside with padding 11 to lie on either side of the horse's spine (not shown). According to the present invention the upper canvas part 10 is provided with two straps 12 on each side adapted to be buckled to buckles 13 on the girth canvas 14 which is provided with loops 15 to receive the

free ends of the straps 12. The inside of the upper part is covered to within, say, three inches of its ends but right up to the edges at the sides with waterproof material 16. Arranged inside the 5 waterproof material 16 and at the upper part thereof are two sheets of mail or chain mail 17 which are adapted, when the device is in use, to extend, say, six and a half inches down on either side of the horse's spine. The two mail or 10 chain mail electrodes 17 are preferably separate from one another, as shown, and are individually connected to the contacts of a plug or socket 18 on the top of the upper canvas part 12 above the horse's spine. The desired electrical connection 15 to the mail or chain mail electrodes 17 is made to the said plug or socket 18 by means of an appropriate lead, the two electrodes being, of course, electrically connected together.

The device according to the present invention is just as simple to put on a horse as an ordinary rugging roller, and is very effective in carrying out electro-therapeutic treatments of the kind above set forth, the plug and socket connection to the mail or chain mail electrodes on the horse's 20 back rendering it a very simple matter to detach the lead immediately so as to leave the horse free if this should be necessary for any purpose.

I claim:

30 A device for carrying out electro-therapeutic treatments of injuries, rheumatism and other ailments by rhythmic muscular contractions in horses, comprising a sheet of flexible material, such as canvas, adapted to lie over the horse's spine, strap means for strapping said sheet of 35 flexible material about the horse's body, at least one sheet of waterproof material covering substantially the whole of the inside surface of said flexible material and secured thereto, at least one mail or chain-mail electrode attached to the inside of the device, padding between said waterproof material and said flexible material on either side of the mid-central line of the device to press said mail or chain-mail electrode into firm contact with the horse's body on either side of the spine when the device is in use, and a readily detachable connection on the outside of said sheet of 40 flexible material electrically connected to said mail or chain-mail electrode.

CHARLES LOVE STRONG.
